[57] CLAIM

The ornamental design for a garage door, substantially as shown and described.

DESCRIPTION

FIG. 1 is a perspective view of a garage door showing my new design;

FIG. 2 is a perspective back view of the garage door shown in FIG. 1;

FIG. 3 is an elevational front view of the door shown in FIG. 1;

FIG. 4 is an end view of the door shown in FIG. 3;

FIG. 5 is a bottom view of the garage door shown in FIG. 3; and

FIG. 6 is a horizontal sectional view, in enlarged scale, taken along the line 6—6 of FIG. 1.
